UNITED STATES PATENT OFFICE.

GEORGE LYON HARVEY, OF CHICAGO, ILLINOIS.

DRAW-GEAR FOR CARS.

SPECIFICATION forming part of Letters Patent No. 773,737, dated November 1, 1904.

Application filed August 14, 1903. Serial No. 169,459. (No model.)

To all whom it may concern:

Be it known that I, GEORGE LYON HARVEY, a citizen of the United States, residing at Chicago, in the county of Cook, State of Illinois, (having a post-office address at 175 Dearborn street, in said city,) have invented certain new and useful Improvements in Draw-Gears for Cars, of which the following is a full and true description, reference being had to the accompanying drawings, showing two embodiments of my invention.

The object of this invention is to provide a novel form of yielding draft-rigging for railway-cars.

The especial point of novelty of the invention consists in providing yieldingly-mounted levers moved by the draw-bar and greatly increasing the resistance of the draft-rigging to pulling or buffing strains.

Broadly stated, the invention includes the placing of the levers in any manner to be moved when the draw-bar is either pulled or buffed, and the movements of the levers may be partially independent of those of the draw-bar. In the preferred embodiments of my invention, however, a pair of levers are loosely carried by or connected with the draw-bar or the draw-bar yoke, so that the initial or shorter movements of the draw-bar will not operate the levers. By preference, also, springs or other yielding connections for the levers, which may well be carried by or connected to the car-frame, are carried by said parts, thus making the entire structure independently of such car-frame.

Referring to the accompanying drawings, Figure 1 is a partly-sectional top view of one embodiment of the invention, wherein an auxiliary draft-spring is used. Fig. 2 shows a right-hand view of Fig. 1, parts of the levers having been removed. Fig. 3 shows a vertical section of Fig. 1. Fig. 4 is a partial vertical section of a modification in which subsills are connected with the draft-rigging, the whole constituting a complete device to be attached to any form of car. Fig. 5 is a cross-sectional view of Fig. 4. Fig. 6 is a fragmentary view showing preferred form and arrangement of the levers. Figs. 7 and 8 are details of the structure of Figs. 1, 2,

and 3. Fig. 9 is a detail showing a modification of Fig. 6.

A indicates a draw-bar, and B a coupler-head. These may be of any desired shape or construction and may be separate or integral. 55

C indicates a draw-bar yoke. The manner of attaching the same is clearly shown in Figs. 3 and 4, wherein the jaws of the yoke engage an enlargement *a* of the tail of the draw-bar.

The draw-bar and yoke may be fitted between the ordinary draft-sills D and E, Figs. 1 to 3 and 7 and 8, or between subsills E' F', Figs. 4 and 5. The former may be the center sills of the car-frame or extensions therefrom, while the latter may be secured to draft-sills 65 or timbers D'.

The draft-sills D and E are slotted, and castings F and G are attached to such sills, with projections of such castings fitting the slots of the sills. As indicated in the drawings, rivets 70 *f* may be used to secure casting F in place and rivets *g* may be used to secure casting G in place. Each casting is provided with a slot *Y*², which is oppositely recessed at *Y*³ *Y*⁴, and in the opposite castings these recesses are reversed—that is to say, in casting G the recesses are at the lower part of slot *Y*², as shown, while in the casting F the recesses are at the upper part of the slot. In Fig. 6 this arrangement and reversal of recesses is more 80 clearly shown, they being formed, however, in the sills themselves, not in attached castings. The castings F and G are provided at their rear ends with projections or ribs, and a spacing-block H, fitted between said ribs, is 85 secured in place by bolts *h h h*.

While the especial novelty of the present invention is in the employment of yieldingly-mounted levers, yet this structure may be advantageously supplemented by ordinary draft-springs for taking up the lighter buffing or pulling strains. For this purpose the levers may be loosely mounted, as indicated in Figs. 1 and 3, in a lever-block I, the rear end of which may be utilized as one of the follower- 95 plates of the usual draft-rigging, while the rear end of the yoke C will loosely engage a follower-plate J, which normally bears against projections Z Z, Fig. 1, of the castings F and G. When the draw-bar is pulled, the fol- 100

lower-plate J will be drawn forward, thus compressing the springs K and L, located between the follower and the lever-block I, and when buffing strains are imparted to the draw-bar the follower J is firmly held by projections Z Z, while the lever-block I compresses the springs.

One manner of mounting the lever-block I in the yoke is shown in Figs. 1, 3, and 8. 10 The block comprises an open-sided frame fitted between the tail *a* of the draw-bar and the springs K L. The lever-block is fitted in the yoke C and is guided by projections *f*² *f*³ *f*³ from casting F (see Fig. 8) and by projections *g*² *g*³ of casting G. In addition the lever-block and the levers, as hereinafter explained, coöperate in maintaining their positions.

One function of the lever-block I is to carry 20 the levers hereinafter described so as to afford a loose connection between said levers and the draw-bar or its yoke. Such a loose connection may, however, be assured in many other ways and be made either directly or in 25 directly with the draw-bar. In Fig. 4 I have omitted the lever-block, using instead thereof short recessed blocks H' and I', the former abutting the tailpiece *a* of the draw-bar and the latter fitted to the rear of the yoke C. It 30 will be noticed also that the structure shown in Fig. 4 does not employ draft-springs K L and the lever-supporting parts are not employed as a follower.

An essential part of my invention is loosely 35 connecting a pair of yielding levers with a draw-bar, and I prefer that the levers shall be carried by the draw-bar or its yoke and also that the springs which are put under strain by the levers shall be entirely supported by the levers themselves. In this manner the levers and springs become floating parts, which will operate irrespective of the amount of slack in the draft-rigging or of injury to or looseness of either of the draft-sills. The connection of draw-bar, levers, and springs also constitutes a complete draft-rigging apparatus, which may be made and sold as such. The preferred embodiment of my 45 invention employs a pair of levers moving independently of each other and carrying springs which are put under strain when the draw-bar is used either for pulling or buffing. I have illustrated in the accompanying drawings an upper lever M and a lower lever N, 50 pivoted together (independently of their connection with the draw-bar or yoke) by a pin O, shown integral with lever N and passing upwardly through an opening in the lever M.

Referring to Figs. 1 and 6, which show preferred forms of levers, it will be seen that each of the levers has curved bearing-surfaces fitting the lever-block or otherwise fitting the draw-bar or yoke and curved bearing-surfaces fitting casting G or draft-sill F'. In Fig. 6 65 the first-named bearing-surfaces of the upper

lever are indicated at M² M², and the second-named bearing-surfaces of the same lever are indicated at M³ M³. The upper lever is also shown as having integral stops m' m² m³ m⁴ at the opposite sides of the short ends, and 70 these constitute square bearing-surfaces, as hereinafter described. Said upper lever is also provided with oppositely-disposed stops m⁵ and m⁶. The lower lever is provided with stops n', n², n³, and n⁴, the latter being shown 75 dotted in Fig. 6.

Normally the levers are in the position shown in Figs. 1, 2, and 3, being held by means of springs. As stated, the springs may be connected or supported by any part of the car or car attachment; but I prefer to have the springs carried entirely by the levers themselves. The embodiment illustrated in the accompanying drawings consists in mounting the springs W X, Fig. 1, upon a rod R 85 at opposite sides of the levers, said springs fitting between end plates U and U' (held on the rod by nuts which fit the threaded ends of the rod) and bearing-plates T and T', which are centrally apertured and loosely fit upon the 90 rod R. Said plates are provided with alined knife-edge ribs t, extending from the outer edge of the plate to the central opening, and these ribs fit notches formed in the levers. Preferably each lever is bent at its long end 95 and provided with alined notches at its opposite sides. Thus lever M has alined notches S and S³ at its sides, and lever N has alined notches S' and S² at its sides, and when assembled all the notches on each side are in 100 line, as shown in Fig. 5. The knife-edge ribs t fit into all four alined notches S' S² S³ S⁴ at each side when the levers are in normal position, being held thereto by the springs. These latter are preferably assembled as shown in 105 Fig. 1, wherein a single set of springs W and X are placed between the end plate U and bearing-plate T, and duplicate sets of springs arranged in series, separated by a washer V, are placed between the end plate U' and bearing-plate T'. Preferably the smaller springs W press the bearing-plates T and T', so as to keep the ribs t in the notches, and the larger springs X merely rest upon the springs W 110 when the parts are in normal position.

The operation of the draft-rigging so far as described is as follows: Whenever a buffing strain is given to the draw-bar, the tailpiece *a* of the latter pushes the lever-block I, and the springs K and L are compressed between the rear of the block and the follower-plate J, and by reason of the space between the block and the forward bearing-surface M² of lever M there will be no movement of the levers if the buffing shock is a light one. 125 If, however, the shock is a heavy one, the levers will be driven rearwardly until the rear curved bearing part M³ (see Figs. 1, 2, and 6) strikes the upper portion of the slot Y², whereupon the lever M will be halted and 130

the continued movement of the draw-bar will force the curved bearing part N^3 of lever N to enter the rearward recess Y^4 , Fig. 2. The interruption of one lever and continued movement of the other results in the movement of both levers about the pivot-pin O , and the outer ends of the levers spread apart, as shown in Fig. 6, putting the springs W and X at both sides of the levers under compression. When a pulling strain is imparted to the draw-bar, the yoke C will draw the follower-plate J forward until the springs K and L are compressed sufficiently to cause the pull to be transferred to the levers M and N , which will be spread apart substantially as hereinbefore explained, but in the direction the reverse of that illustrated in Fig. 6.

In order that the levers may not work out of the draft-rigging, I have shown limiting-stops which do not interfere with the lever movements. Referring to Figs. 1, 2, and 8, it will be seen that an integral projection M^{10} on lever M and a plate N^{10} , secured underneath the extremity of the short arm of lever N , coöperate in preventing shaking of the levers out of the lever-block I . As an alternative the device shown in Fig. 9 may be used. In such device a pin L' , projecting upwardly from the lever M , is arranged to play in a slot formed by a cap-plate K' , secured to the outer side of the draft-sill E .

When both of the levers are bearing against their fulcrum-points and the draw-bar is pressing equally on both levers, (and it cannot do otherwise in the structure illustrated in the accompanying drawings,) there will be but little strain on the pivot-pin O , owing to the fact that the bearing-surfaces of the levers on the sills will be found to be square with the line of the center of the draw-bar or pull, and there is therefore no tendency to spread the draft-sills apart or to draw them together.

It will be obvious that the lever-block I and draft-springs K and L or any of said parts may be omitted, as shown in Figs. 4 and 5. In said figures the levers are loosely fitted in recessed end blocks H' and I' , seated in the yoke C . In said Figs. 5 and 6 I have also shown a manner of applying the draft-rigging to a car by means of subsills. For this purpose I prefer castings E' and F' , which constitute subsills, readily attachable to wooden timbers D' D' or other parts of the car-body D^2 . Said subsills are shown as being spaced apart and strengthened by end block G' and sleeves J' and bolts J^2 .

The illustrated attachment of the springs W X , mounting said springs on the levers themselves, results in a very simple and efficient form of apparatus for taking up shocks. The load on the springs is thrown onto the levers themselves and not transferred to the sills or other portion of the car. The springs will always work properly no matter how

much slack there is in the draft attachment or if one sill should happen to be pushed back out of line with the other. In fact, at all times when the levers are together the springs are in proper position for action. Draft-sills often become misplaced or work loose, and in such cases my new apparatus by reason of having the springs mounted on and following the levers is highly advantageous.

While I have shown and described two embodiments of my improvements, it will be obvious to persons skilled in the draft-rigging art that other forms may be devised which will still be within the scope of my invention.

What I claim is—

1. In a draft-rigging for cars, a draw-bar, a pair of levers carried by and freely movable on the draw-bar, and yielding means for normally drawing the levers together, substantially as described.

2. In a draft-rigging for cars, a draw-bar, a pair of levers loosely pivoted on the draw-bar and adapted to move in opposite directions, and yielding means for normally drawing the levers together, substantially as described.

3. In a draft-rigging for cars, a draw-bar, a pair of levers carried by and freely movable on the draw-bar, and yielding means carried by the levers and operating to draw the same together, substantially as described.

4. In a draft-rigging for cars, a draw-bar, a pair of levers carried by the draw-bar and adapted to move back and forth and in opposite directions, yielding means carried by levers and readily-detachable connections between the levers and the yielding means, substantially as described.

5. In a draft-rigging for cars, a draw-bar, a pair of levers slidably pivoted to the draw-bar and adapted to move back and forth and in opposite directions, and yielding means for drawing the levers together, substantially as described.

6. In a draft-rigging for cars, a draw-bar, a pair of levers carried by the draw-bar and pivoted together by means independent of the draw-bar, and yielding means for normally drawing the levers together, substantially as described.

7. In a draft-rigging for cars, a draw-bar, a pair of levers movable independently of one another in both directions carried by and freely movable on the draw-bar, and means for yieldingly maintaining the levers in normal relation, substantially as described.

8. In a draft-rigging for cars, a draw-bar, a yoke carried thereby, recessed blocks secured to said yoke, a pair of levers loosely carried by the recessed blocks, and yielding means connected with said levers, substantially as described.

9. In a draft-rigging for cars, a draw-bar, connections from the car for loosely supporting the draw-bar, a pair of levers carried by

and freely movable on said bar, yielding means connected with said levers, and stops for causing the levers to move to and from each other upon movement of the draw-bar, substantially as described.

10. In a draft-rigging for cars, a draw-bar, connections from the car for loosely supporting the draw-bar, a pair of levers adapted to be moved by the said bar, yielding means connected with said levers, and stops for causing the levers to move to and from each other upon movement of the draw-bar, substantially as described.

11. In a draft-rigging for cars, a draw-bar, connections from the car for loosely supporting the draw-bar, a pair of levers adapted to be moved by said bar, yielding means connected with said levers, and stops for intercepting the said levers successively upon movement of the draw-bar, substantially as described.

12. In a draft-rigging for cars, a draw-bar, connections from the car for loosely supporting the draw-bar for forward and rearward movements, a pair of levers adapted to be moved by said bar in either direction, yielding means connected with said levers, and stops for successively intercepting the said levers upon movement of the draw-bar in either direction, substantially as described.

13. In a draft-rigging for cars, a draw-bar, a pair of draft-beams, connections from the car for loosely supporting the draw-bar, a pair of levers carried by and freely movable on said bar, yielding means connected with said levers, and means connected with one of the draft-beams for causing the levers to move to and from each other upon movement of the draw-bar, substantially as described.

14. In a draft-rigging for cars, a draw-bar, a pair of draft-beams, one of which is slotted, connections from the car for loosely supporting the draw-bar, a pair of levers carried by and freely movable on said bar and projecting into the slot aforesaid in such position as to be successively intercepted by the walls thereof, and yielding means operated by said levers, substantially as described.

15. In a draft-rigging for cars, a draw-bar, a pair of draft-beams, one of which is provided with an irregular slot, connections from the car for loosely supporting the draw-bar, a pair of levers carried by and freely movable on said bar and projecting into the slot aforesaid in such position as to be successively intercepted by the walls thereof, and yielding means connected with said levers, substantially as described.

16. In a draft-rigging for cars, a draw-bar, a pair of slotted draft-beams, the slots being oppositely disposed, connections from the car for loosely supporting the draw-bar, a pair

of levers loosely pivoted upon and carried by said bar and with the opposite lever-arms loosely playing in the slots aforesaid, and yielding means connected with said levers, substantially as described.

17. In a draft-rigging for cars, a draw-bar, a pair of slotted draft-beams, the slots being oppositely disposed and reversely formed, connections from the car for loosely supporting the draw-bar, a pair of levers loosely pivoted upon and carried by said bar and with the opposite lever-arms loosely playing in the slots aforesaid and being successively intercepted by the walls of the slots upon movements of the draw-bar in either direction, and yielding means operated by said levers, substantially as described.

18. In a draft-rigging for cars, a draw-bar, connections from the car for loosely supporting the draw-bar, yielding means operated directly by the draw-bar, a pair of levers movable independently of one another in both directions, and carried by and freely movable on the draw-bar, and separate yielding means operated by the levers, substantially as described.

19. In a draft-rigging for cars, a draw-bar, connections from the car for loosely supporting the draw-bar, follower devices directly operated by the movement of the draw-bar, yielding means between the follower devices, a pair of levers movable independently of one another in both directions, and carried by and freely movable on the draw-bar, and separate yielding means operated by the levers, substantially as described.

20. In a draft-rigging for cars, a draw-bar, yielding means adapted to be directly operated by the movement of the draw-bar in either direction, a pair of levers movable independently of one another in both directions, and carried by and freely movable on the draw-bar, and separate yielding means supported by the levers and operated thereby, substantially as described.

21. In a draft-rigging for cars, a draw-bar, a pair of levers carried by and freely movable on the draw-bar, two springs of different strength, and connections whereby the springs are successively operated by the levers, substantially as described.

22. In a draft-rigging for cars, a draw-bar, lever connections carried by and freely movable on the draw-bar, two springs of different strength, and connections whereby the springs are successively operated by the lever connections, substantially as described.
